UNITED STATES PATENT OFFICE.

JOSEPH S. LINDEMANN, OF NEW YORK, N. Y.

DESIGN FOR BOTTLE.

Application filed December 1, 1926. Serial No. 19,892. Term of patent 7 years.

To all whom it may concern:

Be it known that I, JOSEPH S. LINDEMANN, a citizen of the United States, residing in the borough of Manhattan, city, county, and State of New York, have invented a new, original, and ornamental Design for Bottles, of which the following is a specification, reference being had to the accompanying drawing, forming part hereof.

Figure 1 is a front elevation of the bottle showing my new design, it being understood that the reverse side of the bottle is the same as that shown in this figure.

I claim:

The ornamental design for bottle as shown.

JOSEPH S. LINDEMANN.
